9 Claims. (Cl. 123—41.36)

1

The present invention relates to cooling systems for the head portion of pistons of high-speed internal combustion engines, more particularly to systems in which a coolant is pumped through a cooling chamber in the head portion of the power pistons by the pump action produced by stationary coolant supply and removal tubes whose ends telescope with coolant supply and removal conduits in and reciprocating with the power piston.

The piston diameter and consequently the power output of high-speed internal combustion engines, particularly as used in motor vehicles, is limited primarily by the temperature of the piston head. The piston diameter can be considerably increased if appropriate cooling, particularly by coolant supplied under pressure through pumping tubes, is provided, the coolant being the oil as used in the crankcase of the engine. Because of the pump action of the tubes, arrangements of this type depend on the engine speed, and usually much more cooling oil is supplied to the piston head than needed. Because of the unfavorable proportion between piston stroke and diameter of the pumping tubes, the oil pressure in the cooling chamber is too great at the conventional high speeds for which the engines are built. During the suction stroke of the pumping tubes, the pressure in the cooling chamber is so much reduced that the flow of oil is interrupted, oil vapor alternates with liquid oil, and air enters the cooling conduits resulting eventually in the formation of undesired foam.

These are the reasons why piston cooling systems as described above, though successful in low-speed engines, could not be applied to high-speed engines.

It is an object of the present invention to provide a cooling system comprising pumping tubes for the pistons of high-speed internal combustion engines which system is independent of the speed of the engine and applicable to engines operating at very high speed.

A further object of the invention is to reduce the undesired pumping effect of the pumping tubes of piston cooling systems of high-speed internal combustion engines and to avoid undesired high and low pressures of the cooling oil in the piston cooling chamber. This is accomplished by providing equalizing means in the piston cooling systems, which means receive a portion of the cooling oil during the pumping stroke of the piston and release it during the opposite stroke. These means comprise preferably one or more spring-actuated equalizing pistons or diaphragms

which are exposed to the pressure of the cooling oil in the cooling chamber of the piston. Stroke and bore of the equalizing pistons and their cylinders, and the pressure of the springs acting on the pistons against the pressure of the coolant, are so arranged as to produce the desired effect on the oil pressure in the cooling chamber. The stroke of the equalizing piston is short relative to its diameter, and the relation between stroke and diameter of the equalizing piston is the inverse of that between the stroke of the power piston and the diameter of the pumping tube, the latter being very small compared with the stroke of the power piston. By proper selection of the pressure of the spring acting on the equalizing piston, the output of the pumping system can be adjusted for best results.

No special valves are needed for controlling the flow of the cooling oil in pistons according to the invention; an oil supply pump may produce the desired effect. A check valve, however, is provided for controlling the flow of oil entering the tube which admits cooling oil into the cooling chamber.

Preferably, the oil flows from the cooling chamber through an outlet tube, and a valve may be provided in the conduit receiving the oil from said outlet tube for closing the oil outlet if the oil pressure in the cooling chamber is below that in the outlet conduit. Without provision of pressure equalizing means according to the invention, such valves would have undesirably large flow areas in high-speed engines. If the above-described equalizing means are provided, only a portion of the oil moved by the pumping tubes need be passed through the valves, and the flow area of the latter need not be much greater than that of the tubes.

With the arrangement according to the invention, the pumping effect of the tubes is generally sufficient to produce the desired oil flow through the cooling chamber. The oil supply pump, if such is provided, need only be large enough to replace the oil which is lost through leakage.

The invention is particularly applicable to pistons comprising a main body and a head member having cooling passages. The equalizing piston according to the invention is guided in a bore of the main body, the head of the equalizing piston forming part of the wall of the cooling chamber in the center of the power piston.

Preferably a protuberance is provided in the center of the power piston for guiding the equalizing piston, oil flowing through said protuberance to the wrist pin bearing for lubrication of the latter.

2

Other objects will appear from the following description of this invention.

The manner in which the foregoing objects are achieved is shown in the appended drawings, wherein like numerals designate like parts throughout the several views, and in which:

Fig. 1 is a longitudinal sectional view of a power piston and part sectional view of the cooling oil circulating system according to the invention;

Fig. 2 is a longitudinal sectional view of the upper part of a modified piston according to the invention;

Fig. 3 is a longitudinal sectional view of a further modification of the head portion of a piston according to the invention, the section being taken along line III—III in Fig. 4;

Fig. 4 is a top view of the piston illustrated in Fig. 3 with the head part removed.

Referring more particularly to Fig. 1, numeral 1 designates a piston having a cooling chamber 2 in which an oil supply tube 3 terminates. A stationary tube 4 extends substantially coaxially into the lower part of tube 3. Substantially diametrically opposite supply tube 3 is an outlet tube 5 for removing the oil from chamber 2. The lower end of tube 5 moves along a stationary tube 6, the latter being coaxial within the former. Tubes 4 and 6 are individually connected with substantially T-shaped connecting parts 7 and 8, respectively, the former receiving oil from a supply pump 9 through conduit 9 and the latter discharging into conduit 10. Conduit 11 on connecting part 7 conducts oil to another piston of the engine, and conduit 12 receives oil from another piston. A spring-loaded check valve 13, 15 is arranged in the connecting member 7 for the coolant supply conduit 4 and a spring-loaded check valve 14, 16 in the connecting member 8 for the coolant discharge conduit 6.

An equalizing piston 20 is received in bore 21 in the upper part of the wrist pin support part of the piston and coaxial of the latter, piston 20 closing the bore against the cooling chamber 2. A spring 22 resting on plate 23 presses piston 20 against the pressure in chamber 2. Plate 23 has marginal portions inserted in recesses 24 of ribs 25 provided in the interior of the power piston 1 for supporting the wrist pin.

Cooling oil is supplied by pump 9' in conduit 9. During the up-stroke of piston 1, oil flows from conduit 9 through connector 7, valve 13, and tube 4, into tube 3, which terminates in cooling chamber 2. The volume made available in conduit 3 during an up-stroke of piston 1 is larger than the volume of the oil supplied by pump 9' to conduit 9, and, since no oil can escape through conduits 5, 6 and 10 because of the check valve 14 in connector 8, the pressure in chamber 2 is reduced and piston 20 forced thereto by spring 22 to compensate the difference between the increase of available space and the volume of the oil supplied by pump 9'. If the pressure in chamber 2 falls below atmospheric pressure, the latter supplements the action of spring 22.

Downward movement of piston 1 causes increase of pressure in chamber 2 and closing of valve 13, and oil, which has been forced into conduits 3 and 4 during the upstroke of the piston, enters chamber 2. At the same time, a certain amount of cooling oil leaves chamber 2 through conduits 5 and 6, valve 14, connector 8, and conduit 10. Equalizing piston 20 is moved outward by the increased pressure in chamber 2. The pressure in chamber 2 decreases during an up-stroke of piston 1 and increases during a down-

stroke; these changes of pressure during the flow of cooling oil through chamber 2, however, are limited by the provision of piston 20, the equalizing effect of the latter depending on the power of spring 22 and the size of the piston. The diameter of the latter is at least as great as its stroke, in most cases substantially greater.

In the modification shown in Fig. 2, the power piston consists of a main body 31 and a head part 32 having internal cooling ribs 33 forming conduits or channels for the cooling oil. The main body 31 has an axial bore 35 receiving an equalizing piston 34. The head part 32 is provided with an internal, axial, tubular extension or guide means 36, projecting downwardly and through a hub part 37 of piston 34. Piston body 31 is provided with an annular projection 38 extending radially inward for supporting springs 43 which extend into the annular recess formed in the underside of piston 34 by the hub portion 37. Springs 43 press the annular piston 34 against the central ribs 33 closing the central cooling channels 30 when the spring-loaded piston 34 overcomes the pressure of the coolant in the cooling channels. The lower end of the interior 39 of guide 36 is closed by a cover 40 having an aperture 41. Transverse bores 42 in the upper part of extension 36 connect the interior 39 with the cooling chamber 30.

The cooling oil is admitted to cooling chamber 30 through a conduit 3' and relieved through conduit 5' in the same manner and the function of the device is the same as in the embodiment according to Fig. 1. A small part of the cooling oil flows from cooling chamber 30 through bores 42, chamber 39, bore 41, into a bore 45 in the wrist pin bearing end 44 of the piston connecting rod for lubricating the wrist pin bearing.

Figures 3 and 4 illustrate a modification of the piston cooling system according to the invention having a plurality of equalizing pistons. The power piston comprises a main part 50 and a head part 51 which is bolted to the former by bolts 52. Cooling oil is supplied through conduit 3'' to the cooling chamber 53 in the interior of the head part 51 in the same manner as in the embodiments shown in Figs. 1 and 2 and is relieved from the cooling chamber through a conduit 5''. The head part 51 is provided with internal cooling ribs 54 projecting into the cooling chamber.

An insert 55 in main part 50 of the power piston has three cylindrical recesses 56, 57, and 58, accommodating pistons 56', 57', and 58', respectively. These pistons are forced upward into the cooling chamber 53 by springs 59, 60, and 61, respectively. Apertures 62, 63, and 64 are provided in the bottom of insert 55 for connecting the chambers 56, 57, and 58, respectively, with the outside.

While the preferred embodiments of this invention are shown and described, modifications other than those disclosed herein may be made without departing from the spirit of the invention, and reference is therefore made to the appended claims for a definition of the scope of this invention.

I claim:

1. A compensated cooling system for the head portion of a power piston for high-speed internal combustion engines, comprising a cooling chamber disposed in the head portion and being completely closed against the cylinder in which the piston operates, coolant circulating conduits connected and reciprocating with the power piston and terminating in said cooling chamber, stationary coolant supply and removal tubes indi-

vidually extending into said conduits, and compensating means connected with said piston and communicating with said chamber and being adapted to be actuated by the coolant pressure in said chamber and to compensate, at a predetermined rate, the fluctuations of coolant flow through and of coolant pressure in said chamber caused by the pump action of said conduits and of said stationary tubes.

2. A cooling system as defined in claim 1, said compensating means comprising a movable member forming a movable wall portion of said chamber and being adapted to decrease the internal volume of said chamber upon an up-stroke of the power piston and to increase the internal volume of said chamber upon a down-stroke of the power piston.

3. A cooling system as defined in claim 1, said compensating means comprising a piston chamber connected and communicating with said cooling chamber, an equalizing piston in said piston chamber, and a spring resting on the power piston and on said equalizing piston for pressing the latter against the pressure of the coolant in said cooling chamber.

4. A system as set forth in claim 3, the diameter of said equalizing piston being at least as great as the stroke of the equalizing piston.

5. A system as set forth in claim 3, said piston chamber being disposed coaxially of the power piston.

6. A compensated cooling system for the head portion of a power piston for high-speed internal combustion engines, comprising a cooling chamber disposed in the head portion and being completely closed against the cylinder in which the piston operates, coolant circulating conduits connected and reciprocating with the power piston and terminating in said cooling chamber, stationary coolant supply and removal tubes individually extending into said conduits, a check valve in each of said stationary tubes, and compensating means connected with said piston and communicating with said chamber and being adapted to be actuated by the coolant pressure in said chamber and to compensate, at a predetermined rate, the fluctuations of coolant flow through and of coolant pressure in said chamber caused by the pump action of said conduits and of said stationary tubes.

7. A compensated cooling system for the head portion of a power piston for high-speed internal combustion engines, comprising cooling channels disposed in the head portion and being completely closed against the cylinder in which the piston operates, coolant circulating conduits disposed within and connected and reciprocating with the power piston and communicating with said channels, each of said conduits comprising a straight part parallel to the longitudinal axis of the power piston, stationary coolant supply and removal tubes individually extending into

said straight parts, a main piston part connected with the head portion of the said power piston, a piston chamber coaxial of and within said main piston part and communicating with said channels, and a spring-loaded equalizing piston in said piston chamber.

8. A cooling system for the head portion of a power piston for high-speed internal combustion engines, comprising a coolant, a cooling chamber in the head portion of the power piston, coolant conduits in and reciprocating with the power piston and terminating in said cooling chamber, stationary coolant supply and removal tubes individually extending into said conduits, a piston chamber extending from said cooling chamber axially of the power piston, a piston rod having a wrist pin bearing end, a tubular guide means connected with said head portion, extending through said piston chamber coaxially of the power piston, and terminating adjacent to said bearing end, an annular equalizing piston in said piston chamber and disposed around said guide means, and spring means resting on said power piston and on said equalizing piston for pressing the latter against the pressure of the coolant in said cooling chamber, said coolant being a lubricating oil and the interior of said guide means communicating with the cooling chamber and receiving oil therefrom and discharging it on said bearing end.

9. A compensated cooling system for the head portion of a power piston for high-speed internal combustion engines, comprising a cooling chamber in the head portion of the power piston, coolant conduits within and connected and reciprocating with the power piston and terminating in said cooling chamber, stationary coolant supply and removal tubes individually extending into said conduits and pumping coolant through said cooling chamber upon reciprocation of the power piston, compensating means connected with the power piston and communicating with said cooling chamber for compensating the fluctuations of coolant flow through and of the coolant pressure in said chamber at a predetermined rate, and a coolant supply pump connected with said supply tube for maintaining said supply tube filled with coolant at all operating conditions of said system.

KARL MAYBACH.
